UNITED STATES PATENT OFFICE.

GEORGE E. HEATH, OF CURTIS, NEBRASKA.

CORN-PLANTER.

SPECIFICATION forming part of Letters Patent No. 544,581, dated August 13, 1895.

Application filed March 29, 1895. Serial No. 543,726. (No model.)

To all whom it may concern:

Be it known that I, GEORGE E. HEATH, of Curtis, in the county of Frontier, State of Nebraska, have invented an Improved Corn-5 Planter, of which the following is a specification.

This invention relates generally to corn-planters, and particularly to certain improvements upon my planter for which application 10 for Letters Patent was made December 8, 1894, Serial No. 531,261.

The objects of the present invention are to provide a reel for placing the check-row wire and also to provide certain devices for dropping 15 said wire whenever desired.

Another object is to provide an improved means for operating the dropper-plates of the seed-boxes, and a still further object is to provide a novel means of adjusting the height 20 of the lister-plow.

With these objects in view my invention consists in the peculiar construction of the several parts and the novel combination or arrangement, all of which will be fully described hereinafter, and pointed out in the 25 claims.

In the drawings forming a part of this specification, Figure 1 is a longitudinal sectional view of my planter. Fig. 2 is a detail plan 30 view; Fig. 3, a detail view of the dropper-plate and actuating-arms; Fig. 4, a detail view of same; and Figs. 5, 6, and 7 show details of construction.

In carrying out my invention I employ a 35 framework A, composed of the front and rear sections a and a', respectively, said rear part being mounted upon the axle C the same as in my prior device, and the seat and its frame, the means of connecting and adjusting the rear 40 portion, the seed-boxes and lister-plows are all substantially of the same construction as already shown and described in my prior application.

A reel D is mounted upon the rear portion 45 of the forward frame-section, said reel being intended to carry the check-row wire while placing the same in position for operation, and after said wire is properly placed is passed through the pulleys as heretofore and operates 50 to drop the seed the same as usual. The reel is formed with a wheel D' at one side of the same, and bearing upon the periphery of this

wheel is a spring-pressed brake-shoe, which renders the revolution of the wheel steady and prevents the check-wire unreeling too rapidly. As before stated, the reel is only used in placing the wire, said wire being attached or anchored at one side of the field and the machine driven across the field in order to accomplish this operation, and inasmuch as the wire passes beneath the machine during this operation and through the operating-lever the machine will, of course, be planting during such operation. After the wire has been placed and it is intended to operate the machine thereby said wire is passed through the pulley F, carried at the forward end of the tongue, the pulley G at the forward end of the frame, the pulleys H, mounted about midway of the forward section of frame, and 60 the pulley I, arranged at the extreme rear end of the main frame.

The pulley F at the forward end of the tongue is suspended upon a spring-actuated bolt G', and connected with said bolt is a cord 75 or chain G², which connects with a lever K, mounted upon the side of the beams of the forward section of frame, so that by drawing back the lever the spring-bolt will be drawn into its housing and the pulley F dropped. 80

The pulleys H H are mounted upon the lower ends of right-angled rock-shafts L L, journaled upon the side beam of the forward section, their horizontal members being connected by means of a rod L', and a link or rod 85 L² serves to connect the said rod L' with lever K, so that when said lever is drawn back to release the pulley F the pulleys H H will be thrown around to a longitudinal position and thereby drop the wire. 90

As before stated, the seed-boxes of this device are substantially the same as those shown and described in my prior application; but the dropping-plates and means for operating the same are novel, said plate M having a series 95 of teeth m formed upon its outer edge, each tooth having a beveled edge m' and an undercut edge m². For operating said plates I employ a lever N, pivoted centrally upon the forward section of the frame and operated as usual, said lever having the operating-arms O pivotally connected therewith and having arrow-headed ends o for engagement with the teeth m of the dropper-plate, the said ends rid-

ing up the bevel m' and dropping by gravity behind the undercut edge m^2 , thus avoiding the use of spiral springs for throwing the arms into engagement with the plate. For seeding 5 I employ but one arm, while in drilling I employ two arms, operating the plate from opposite sides.

For the purpose of adjusting the lister-plows I secure the beams P thereof to the cross-beam 10 of frame by means of an adjustable staple P' , and between the cross-beam of frame and beam of plow I interpose a wedge-shaped casting-piece R , slotted longitudinally to receive the staple P' and its set-screw r , by 15 means of which the casting can be adjusted in or out, and thus raise or lower the beam of the plow.

It will thus be seen that I have improved my previous construction by the addition of 20 a reel, by dispensing with the spring-actuated arm for operating the dropper-plate, by providing an improved form of dropper-plate, and by providing improved means for guiding and releasing the check-wire, the operation 25 of all said parts being apparent from the description and illustration thereof.

Having thus described my invention, what I claim, and desire to secure by Letters Patent, is—

1. In a check row corn planter, the combination with a frame, of the guide pulleys F , G , and H , a spring bolt G , for supporting the pulley F , a rod G^2 connected to said spring bolt, a lever K to which said rod is attached, the pitman L' for turning the pulleys H , and 35 the link L^2 , connecting said pitman with the lever K , substantially as shown and described.

2. The combination with a cross-beam of the frame, of the beam of a plow, the staple P' , through which said plow beam passes, the 40 slotted wedge shaped block R , interposed between the top of the plow beam and the bottom of the cross beam, and means for securing said block, to the cross beam, substantially as shown and described.

In testimony whereof I affix my signature in the presence of two witnesses.

GEORGE E. HEATH.
